SIFTPROOF CARTON

Thomas F. Cass, Jr., Wayne, Ill., assignor to Container Corporation of America, Chicago, Ill., a corporation of Delaware

Application April 28, 1944, Serial No. 533,128

4 Claims. (Cl. 229—14)

1

The invention relates to sift-proof cartons, and more particularly to cartons especially adapted for packaging finely divided material, such as salt, sugar, soap flakes and washing powder. The principal object of the invention is to provide a carton which may be tightly sealed so as to prevent loss or sifting of material from the carton. Another object of the invention is to provide a sift-proof, lined carton which may be moisture-proof and grease-proof.

In accordance with the preferred embodiments of the invention, these are accomplished by providing a paperboard blank from which the carton is to be formed with a lining sheet preferably secured thereto by means of an adhesive, such as amorphous wax or a similar composition. The blank is then die-cut to form end flaps, but instead of cutting the entire flap through the paperboard and liner a portion of the liner is left uncut so that when the inner end flaps are folded downwardly the uncut portions of the liner will draw away from the adjacent flaps and form a bellows corner, and when the seal is completed by folding down the outer flaps a completely sift-proof carton is provided.

The invention will be more readily understood by reference to the accompanying drawing and the following detailed description, in which are set forth an illustrative embodiment of the inventive thought.

In the drawing:

Fig. 1 is a plan view of a lined blank from which the carton may be formed;

Fig. 2 is a view of the carton embodying the invention, with all but one of the end flaps turned down, the turned down outer end flap being partially broken away to show the bellows corner by means of which the sealing is obtained;

Fig. 3 is a detailed fragmentary view of one of the corners of the box before the end flaps have been turned down, this view showing the extension sealing flaps of both the carton and the liner;

Fig. 4 is a sectional view on the line 4—4 of Fig. 1;

Fig. 5 is a sectional view on the line 5—5 of Fig. 2, but with the last of the sealing flaps closed; and

Fig. 6 is a detail perspective view on an enlarged scale showing one of the corner seals.

Referring to the drawing in detail, and with particular reference to Fig. 4 thereof, it will be noted that the carton is formed of two layers, one designated at A comprising the main or stock portion of the carton and being preferably

2

formed of ordinary paperboard, and the other layer comprising a suitable liner B which may either be a paper sheet secured to the paperboard portion by means of an adhesive such as amorphous wax or similar composition, or may be a moisture and vapor-proof substance such as glassine, parchment, Cellophane, "Pliofilm" or the like.

Referring to Fig. 1, the carton blank as shown comprises a body portion including a pair of wide panels 10, 10 and a pair of narrow panels 11, 11, although if desired all the panels could be of the same width. Extending beyond one of the narrow panels 11 is a lined sealing flap 12, while extending from the opposite panel 10 is an extension 13 of the liner B only, the stock portion A of the carton terminating at the vertical line 15 and its extensions 22, 22. The panels 10, 11 and 12 are separated from each other by any suitable means, as for example vertical score lines 14, 14, while horizontal score lines 16, 16 may be provided for separating the main panels 10 and 11 from sealing panels 17 and 18, the reference numerals 17 designating the relatively wide extension flaps, and the reference numerals 18 designating the narrow extension flaps projecting beyond the panels 11, 11. The liner extension 13 may also be provided with extensions 19, 19 separated therefrom, if desired, by suitable score lines.

To form the sealing or extension flaps 17 and 18 the blank is die-cut in such a manner that slots 20 are formed separating the flaps, which slots extend entirely through the paperboard portion 35 A of the blank to the horizontal lines 16, and also extend through the liner down to points a short distance from the fold line, leaving unsevered portions 21 which, when the extension flaps are folded down, are adapted to form corner seals which effectively prevent sifting of the material. Similarly the liner flap portions 19 are separated from the flaps 17 by means of cuts 22 which extend down to uncut portions 23 corresponding with the uncut portions 21, 21 at the ends of the die-cuts 20.

In setting up the box the panels are folded to tubular form along the lines 14, 14 and are secured in place by means of the external flap 12 and the internal liner extension 13, these being preferably secured in place by means of suitable adhesive. These flaps in their securing position are indicated in Fig. 3. It will be noted that as shown the flap 12 terminates short of the sealing flaps 17 and 18, whereas the portions

19, 19 of the liner extension 13 extend to the outer limits of the sealing flaps 17 and 18.

To close the carton the narrow flaps 18, 18 are first folded downwardly into horizontal position, as illustrated in Fig. 2. As these flaps are folded into sealing position the uncut portions 21, 21 of the liner will tear away from the adjacent flaps 17, 17 and form a bellows corner 25. When the seal of the box is completed on folding down the outer flaps 17, 17 the bellows corner will be folded over, as indicated in Fig. 5, and will be retained between the various layers of the end sealing flaps, thus effectively preventing sifting of the contents.

The invention has been described in detail for the purpose of illustration. It will be obvious that numerous modifications and variations may be resorted to without departing from the spirit of the invention. Thus the composition of the liner may be varied as desired, and also the flap extensions 12 and 13 may be varied or omitted, provided other suitable corner sealing means is substituted. The size of the bellows corners 25, 25 will be dependent on the length of the cuts 21, 21, but should preferably be comparatively smaller and only sufficient to effectively close the corners of the cartons.

I claim:

1. A folding carton formed from a sheet of paperboard having a sheet of lining material adhesively secured to its entire inner surface including a plurality of adjacent side wall panels and a plurality of closure flaps integrally joined to said panels along a score line, said closure flaps being defined from adjacent flaps by cuts extending completely through said sheet of paperboard substantially to said score line and extending through said sheet of lining material only to points slightly but substantially removed from said score line.

2. A folding carton blank having elements adapted to provide a sift-proof closure at least at one end thereof comprising a sheet of paperboard having a sheet of lining material adhes-

ively secured to its entire inner surface, said blank being cut and scored to provide a plurality of side wall panels and closure flaps integrally joined to said panels along a score line, said closure flaps being defined from adjacent flaps by cuts in said sheet of paperboard extending outwardly from said score line and cuts in said sheet of lining material coinciding with said first-mentioned cuts but extending outwardly only from points substantially outwardly spaced from said score line.

3. A folding carton formed from a sheet of paperboard having a sheet of lining material secured to its entire inner surface by means of an amorphous wax or similar adhesive comprising four rectangular side wall panels having integral rectangular closure flaps joined thereto along a score line, a lateral extension of said paperboard on one of said side wall panels adapted to be secured to another of said side wall panels to form a tubular carton body, a lateral extension of said lining material on one of said side wall panels, and an end extension on said last-mentioned lateral extension, the paperboard portions of said closure flaps being defined from each other by cuts therein extending outwardly from said score line and the lining material portions of said closure flaps and said end extension being defined from each other by cuts therein extending outwardly only from points substantially outwardly spaced from said score line.

4. A folding carton formed from a sheet of paperboard having a sheet of lining material secured to its entire inner surface by means of an amorphous wax or similar adhesive including a plurality of adjacent side panels and a plurality of closure flaps integrally joined to said panels along a score line, said closure flaps being defined from adjacent flaps by cuts extending completely through said paperboard sheet outwardly from said score line and extending outwardly through said sheet of lining material only from points spaced outwardly of said score line.
